UNITED STATES PATENT OFFICE

147,857

DESIGN FOR A LAMP SHADE

Karl O. Larson, Minneapolis, Minn.

Application February 10, 1945, Serial No. 117,871

Term of patent 7 years

(Cl. D48—16)

To all whom it may concern:

Be it known that I, Karl O. Larson, a citizen of the United States, residing at Minneapolis, in the county of Hennepin and State of Minnesota, have invented a new, original, and ornamental Design for Lamp Shade, of which the following is a specification, reference being had to the accompanying drawing, forming part thereof.

Fig. 1 is a view in front elevation of the lamp shade showing my new design; and

Fig. 2 is a view in side elevation thereof.

The shading on the drawing represents contrasting colors.

I claim:

The ornamental design for a lamp shade, as shown and described.

KARL O. LARSON.
